UNITED STATES PATENT OFFICE.

THEODORE SCHISGALL, OF NEW YORK, N. Y., ASSIGNOR TO TRAVELIGHT MFG. CO., OF PHILADELPHIA, PENNSYLVANIA, A CORPORATION OF DELAWARE.

COMBINED CHILD'S ROCKING-CHAIR, STATIONARY CHAIR, CRIB, AND BABY-CARRIAGE.

1,274,458.

Specification of Letters Patent.

Patented Aug. 6, 1918.

Application filed December 22, 1917. Serial No. 208,354.

To all whom it may concern:

Be it known that I, THEODORE SCHISGALL, a citizen of the United States, residing in the city and county of New York, State of New York, have invented a new and useful Combined Child's Rocking-Chair, Stationary Chair, Crib, and Baby-Carriage, of which the following is a specification.

My invention consists of a device composed of a body having thereon members whereby the device may be converted into a child's rocking chair, stationary chair, crib, and baby carriage, one from the other at will, the nature and operation of said members being hereinafter described.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a side elevation of the device forming a rocking chair.

Fig. 2 represents a side elevation of the same converted into a stationary chair.

Fig. 3 represents a central longitudinal vertical section of the device converted into a stationary chair and crib.

Fig. 4 represents a top or plan view of a portion thereof.

Fig. 5 represents a side elevation of a portion of one of the legs employed, and the adjacent portion of the side piece of the body and the securing studs, screws or pins in section, all on an enlarged scale.

Fig. 6 represents a side elevation of the device forming a baby carriage.

Fig. 7 represents a central longitudinal vertical section thereof.

Fig. 8 represents a view similar to Fig. 5, showing the leg in a different position.

Fig. 9 represents a section of a portion on line 9—9 Fig. 6, on an enlarged scale.

Fig. 10 represents an end view of a portion of Fig. 6 on an enlarged scale.

Fig. 11 represents a perspective view of a portion of the axle and appurtenance shown in Figs. 6, 7 and 10 on an enlarged scale.

Fig. 12 represents a vertical section of the parts shown at the lower left hand end of Fig. 10.

Fig. 13 represents an elevation of a washer employed in some of the figures.

Fig. 14 represents a section on line 14—14 55 Fig. 8.

Similar numerals of reference indicate corresponding parts in the figures.

Referring to the drawings:

1 designates the side pieces or members 60 of the device, the same having the profile of a child and having their under side curved forming rockers 2, as members of a rocking chair, as will be hereinafter referred to.

On the exterior of said side pieces 1 are 65 the legs 3 and between said pieces is the seat 4 which may be occupied by a child, the back member 5 against which the child may rest, the tray 6 which is carried by the arms 7 which are connected with the back by the 70 pivots 8, and the floor 9 which is secured to the side pieces, it being readily seen that when the parts are in position as shown in Fig. 1 the body of a well defined child's 75 rocking chair is formed.

It will be noticed that on the interior of the side pieces 1 are the blocks 10 which are secured to the back member 5 adjacent to the pivots 11 of the lower portion 12 of said back member 5, as most plainly shown in 80 Fig. 7. The pivotal ends of the arms 7 are formed with shoulders 13 which are adapted to abut the adjacent ends of the blocks 10 and so retain the arms and consequently the tray in operative position, as shown in 85 said Fig. 1, whereby it may render service for holding various articles in front of the child and prevent the latter from slipping forward from the seat 4.

Each leg 3 is however held in horizontal 90 position on the side piece 1 and for this purpose it has in what may be termed its inner end the recess 14, and adjacent thereto the tongue 15 which forms the fork 16.

Connected with the piece 1, are the screws 95 or pins 17 which are adapted to occupy either branch of the fork 16 and so by their engagement with the opposite walls of the tongue 15, as to straddle the same, see Fig. 8, the leg is held in the position shown in 100 Figs. 1, 6, and 7. This is assisted by the detent 18 on the outer end of the leg, the same being adapted to engage either tooth or serrations 19 in the rear edge of the side piece 1. The leg may however be drawn out 105 clear of said serrations and the studs 17 then occupy the recess 14 whereby the leg may be turned to a comparatively vertical position,

as shown in Fig. 2, resting on the floor when the pins occupy one branch of the fork 16, as shown in Fig. 5.

When the device is converted into a child's stationary chair, as shown in Figs. 2 and 3, the tray 6 may be thrown upwardly, rearwardly and downwardly, as shown in Fig. 3, when the arm 7 will abut the block 10 as shown in said figure, and so occupy an inoperative position, as shown in Fig. 3. This results when the device is to be converted into a crib, as shown in said Fig. 3, in which case the block 10 is connected pivotally with the side piece 1 and also by the set screw 20 which passes into the segmental slot 21 in the side piece, and so adapts the block, and consequently the back member 5 to change their angles from that shown in Fig. 1, to that shown in Fig. 3. The seat 4 is connected with the side piece 1 by the bolt 22 as a pivot therefor, and the seat is also connected with the side piece by the set screw 23 which passes through the same into the segmental slot 24 in the side piece 25 and is tightened by the thumb nut 25 on said set screw. By these provisions the angularity of the seat is changed to suit the back member 5, and thus the device is converted into a child's crib as also shown in said Fig. 3.

In order to convert the device into a baby or child's carriage, I employ the wheels 26 which are mounted on the axle 27, the latter being provided with the spring pressed catch 28, which is adapted to have its nose engage with the slotted bracket 29 on the floor 9 of the body of the device as a connection for said axle with said body at or about the center thereof.

40 In the end portions of the top of said axle are the recesses 30 in which are seated the rockers or rocking portions of the side pieces 1 of the body, said portions being raised from the floor and pinned immovably in said recesses by the dowels 31 which enter said pieces and axle, and thus the axle is firmly connected with the floor and side pieces, it being evident referring to Figs. 6 and 7 that a well defined child's or baby carriage is produced in which case the angles of the back member 5, and seat 4 have been properly adjusted, and the tray 6 and legs 3 have been placed in inoperative position may be adjusted. When, however, a rocking chair or crib is required the catch 28 is operated to be released of the bracket 29 when the axle with its appurtenances may be removed from the side pieces 1, and so the rockers or rocking portions may again rest on the floor as in Figs. 1, 2, and 3 according to requirements of a rocking chair, stationary chair, or crib.

45 In Figs. 13 and 14 I show a washer 32 in the walls of the opening of which are re-

cesses 33 to have the screws or studs 17 occupy the same, so as to prevent rotation of the washer, the latter being interposed between the heads of said screws or studs and the adjacent faces of the legs 3, and so preventing outer disconnection of the latter. 70

The floor 9 is connected with the side pieces 1 by the bolts 34 which pass through said pieces into the sides of the floor and tightened by suitable means, said floor being readily removable from the side pieces 75 allowing the wheels and their axles to be placed in knock down condition, this being also true of the seat 4, the back supporting member 5, the tray 6 and its arms 7, and the legs 3, said parts being readily reassembled as is evident.

Having thus described my invention what I claim as new and desire to secure by Letters Patent, is:—

1. A rocking body having a side piece, a leg pivotally connected with said side piece and adapted to prevent rocking of said body, and coöperating studs and means for holding said leg in either a vertical or a horizontal position and supplemental means on said side piece engaging the free end of the leg for assisting in holding the leg in horizontal position. 80

2. A rocking body having a side piece, a leg pivotally connected with said side piece and adapted to prevent rocking of said body, coöperating studs and means for holding said leg in either a vertical or a horizontal position, and coöperating serrations and a detent on said leg and side piece for assisting in holding the leg in horizontal position. 90

3. A rocking body, a back supporting member, a floor, a movable leg adapted to prevent rocking of said body, means for holding the leg in either horizontal or vertical position, an axle, and means for firmly connecting the axle with said floor and the side pieces of said body. 105

4. A rocking body having thereon a seat, a back supporting member, a floor, a slideable leg, the latter being adapted to prevent rocking of said body, means for holding said leg in either its vertical or horizontal position, an axle connected with said floor 110 and removable therefrom, and means for removably connecting said floor with said body and means for firmly connecting the axle with the floor and side pieces. 115

5. A rocking body, an axle, wheels mounted thereon, said axle having recesses in which the lower ends of the side pieces of said body may be seated, and means for removably connecting said axle with the adjacent portions of said body, and dowels 120 adapted to enter said pieces and axle and connect said axle with said piece. 125

6. A rocking body, an axle, wheels mounted

ed thereon, said axle having recesses in which the lower ends of the side pieces of said body may be seated, means for removably connecting said axle with the adjacent portion of said body, dowels adapted to enter said pieces and axle and connect said axle and pieces, and a catch on said axle

5 adapted to engage a bracket member on the adjacent portion of the body adapted to removably connect said axle with said portion. 10
